(57) **CLAIM**

We claim the ornamental design for a solar power generation assembly, as shown and described.

DESCRIPTION

FIG. 1 is a bottom and left perspective view of a first embodiment of a solar power generation assembly showing our new design.

FIG. 2 is a left side perspective view thereof.

FIG. 3 is a top and right side perspective view thereof.

FIG. 4 is a left side elevational view of a second embodiment of a solar power generation assembly shown in FIG. 1.

FIG. 5 is a left side elevational view of a third embodiment of a solar power generation assembly shown in FIG. 1; and,

FIG. 6 is a left side elevational view of a fourth embodiment of a solar power generation assembly shown in FIG. 1.

The broken lines in the figures show portions of the solar power generation assembly which form no part of the claimed design.

1 Claim, 6 Drawing Sheets
